UNITED STATES PATENT OFFICE.

ADALINE A. ROCKWELL, OF NEW YORK, N. Y.

DESIGN FOR RUCHES.

Specification forming part of Design No. **7,462**, dated May 26, 1874; application filed May 4, 1874.
[Term of Patent 3½ years.]

To all whom it may concern:

Be it known that I, ADALINE A. ROCKWELL, of the city, county, and State of New York, have invented a Design for Ruches, of which the following is a specification:

The nature of my design is fully represented in the accompanying drawing, to which reference is made.

Figure 1 is a side view, as seen from the exterior, of a ruche, in part, made in accordance with my new design; and Fig. 2, a diagram or outline view representing a transverse profile of the same on the line *x-x*.

Similar letters of reference indicate corresponding parts.

A represents the exterior, and B the interior, portions or borders of the ruche. The interior portion or border B is formed of a ruffle or fluting, the transverse section of which is mainly of circular or loop-like profile, as shown in Fig. 2, with rolling or rounded outer edges

b, as shown in Fig. 1, and terminating below in flattened or straight continuations *c*, the two portions or borders A B lying back to back. The outer portion or border A is composed of independent flutes or cross up-and-down ruffles arranged side by side, also curving outwardly from above, and of a spread loop-like form in their longitudinal section meeting below, as at *d*, the straight continuations *c* of the inner portion or border B, and with rolling or outer edges *c*, which occupy a transverse relation to the rolling or rounded outer edges *b* of the inner portion B.

What I claim as my invention is—

A design for ruches, substantially as described, and shown in the annexed drawing.

ADALINE A. ROCKWELL.
